COMBINATION FIREPLACE AND HEATER

Bernard R. Rose, West Los Angeles, Calif., assignor to
Dyna Manufacturing Co., Los Angeles, Calif., a corporation of California

Filed Apr. 13, 1964, Ser. No. 79,455

Term of patent 14 years

(Cl. D81—7)

FIGURE 1 is a front elevation of a combination fireplace and heater showing my new design.

FIGURE 2 is a side elevation of FIGURE 1.

FIGURE 3 is a rear elevation of FIGURE 1.

FIGURE 4 is a top plan view of FIGURE 1.

FIGURE 5 is a bottom plan view of FIGURE 1.

I claim:

The ornamental design for a combination fireplace and heater, substantially as shown.
